UNITED STATES PATENT OFFICE.

HARVEY C. BAKER, OF CHICAGO, ILLINOIS.

WINDOW-AWNING.

1,335,930.

Specification of Letters Patent.

Patented Apr. 6, 1920.

Application filed May 1, 1919. Serial No. 294,031.

To all whom it may concern:

Be it known that I, HARVEY C. BAKER, a citizen of the United States of America, and a resident of Chicago, in the county of Cook, 5 State of Illinois, have invented certain new and useful Improvements in Window-Awnings, of which the following is a specification.

This invention relates to that class of window awnings in which a spring impelled awning roller normally maintains the awning sheet in a wound condition, and which with a manual rotation of said roller against the stress of its actuating spring permits of 15 a descent of the awning sheet and accessories into a down or unfolded condition by gravity, to be engaged and held in such unfolded condition by an automatically operating latch mechanism. And the present improvement has for its various objects:—

To provide a structural formation and association of the guiding parts and mechanisms of the awning sheet adapted to afford a ready and convenient detachment thereof 25 from the window frame, and a folding together of said parts for convenient storage for further use, or during the cleaning and painting of the building front.

To provide a simple and efficient structural formation and association of the stay rod of the awning sheet and the supporting brackets of the rod adapting the same for ready detachment when desired, and at the same time afford a secure attachment of said 35 rod in place.

To provide a simple and efficient structural formation of the awning extending arms, adapting them for effective operation regardless of inequalities in the setting of 40 the fixed upright guide rails upon which the bearing carriage of said rails have movement, and which in addition permits of a folding of the arms into a compact compass for storage and transportation.

45 To provide a simple and efficient automatically operating latch mechanism adapted to securely hold the awning sheet in its lowered or unfolded condition, and capable of ready release by a further manual rotation of the awning roller in an awning low-

ering direction, and which also is adapted to automatically move into such release condition when a windstorm of sufficient force to endanger the awning and its attaching means, arises, all as will hereinafter more 55 fully appear.

In the accompanying drawings:—

Figure 1, is a front elevation illustrating the general arrangement of parts and mechanisms in the present invention, parts being 60 shown in section.

Fig. 2, is an enlarged detail sectional elevation in the same direction as Fig. 1, of an upright guide rail and associated parts.

Fig. 3, is a transverse sectional elevation 65 on line 3—3, Fig. 1, with the awning sheet shown in dotted lines in its fully spread or extended condition.

Fig. 4, is an enlarged detail transverse sectional elevation, showing in full lines the 70 automatic latching mechanism in its inactive condition during the descent of the awning sheet to its unfolded position, and in dotted lines in its still inactive condition 75 as the awning extending arm is nearing the fully unfolded position of the awning sheet shown in Fig. 1.

Fig. 5, is a companion view showing said automatic latching mechanism lowered to a 80 position to effect a release from its active position in which it acts to hold the awning sheet in a properly unfolded condition.

Fig. 6, is a detail section of the same on line 6—6, Fig. 5.

Like reference numerals indicate like 85 parts in the several views.

Referring to the drawings, 1 designates a window frame at the upper portion of which is mounted in the usual detachable manner a spring actuated roller 2 of the type in 90 which the motor spring tends to wind up the flexible awning sheet 3, with said roller 2 provided with an end drum or sheave 2' for a manually actuated cord 4 by which the roller 2 is caused to rotate and unwind the 95 awning sheet 3 against the tensions of the motor spring aforesaid, as usual in the present class of awnings.

5 designates a holding cleat secured to the window frame and adapted to receive and 100

fasten the operating cord 4 aforesaid, in position convenient for access.

- 6 designates the usual transverse stay rod arranged intermediate the height of the window frame 1 for imposing an approximately vertical condition on the upper portion of the awning sheet 3 in a spread or unfolded condition of the same. In the present improvement said stay rod 6 is mounted 10 in a detachable manner in the window frame so as to be capable of ready detachment when it is desired to have the awning sheet 3 spread its entire length in an oblique direction as illustrated in dotted lines in Fig. 3, as well as during non-use of the awning or when cleaning or painting the front of the building. To the above end the following structural arrangement of parts is provided.
- 20 7 designates a socket plate attached to one side of the window frame and having a socket recess for the reception of an end of the stay rod 6.
- 8 designates a companion socket plate attached to the opposite side of the window frame and having a socket recess for the reception of the other end of the stay rod 6, and in the present invention said socket recess is made of some length to permit of 30 sufficient longitudinal movement of the stay rod 6 therein to admit of the other end of the stay rod being inserted in the socket recess of the aforesaid socket plate 7, and said rod is pushed longitudinally into said recess and yieldingly maintained in proper position by a spring 9 and movable abutment disk 10 arranged in the socket recess of the socket plate 8 as shown in Fig. 1.
- 11 designates the upright guide rails or rods of the awning frame, mounted in a detachable manner at the respective sides of the window frame 1 in upper and lower bracket members 12 and 13 formed with socket recesses for the reception of the respective ends of said rails or rods, and in manner similar to that above described in connection with the stay rod 6, and as follows:
- 14 designates an abutment disk and 15 an actuating spring therefor, arranged in an enlarged upper portion of the socket recess of each upper bracket member 12 aforesaid, adapted to permit sufficient longitudinal movement of a guide rail 11 in said recess to admit of the opposite end rail being inserted in the socket recess of the lower bracket member 13, into which said rail end is pushed and the guide rail yieldingly maintained in proper position by the spring 60 and abutment disk aforesaid.

16 designates sliding heads or blocks moving on the guide rails 11 aforesaid, and providing a pivoted abutment for the swinging arm 17 by which the lower end of the awning

sheet 3 is pushed out in an unfolding 65 movement of the awning. In the present improvement one end of each awning extending arm 17 is connected to the side of a sliding head 16 by a pivot pin or stud 18 disposed longitudinally of the awning structure, and to one end of the usual stretcher rail or rod 19 at the lower end of the awning sheet 3 by pivot pins 20 disposed transversely of the awning structure and connecting the other of said awning extending arm 17 to a head or block 21 pivotally mounted on an end of the stretcher rail 19 aforesaid. With the above described pivotal connection and arrangement of parts the awning extending arms 17 will be free to operate regardless of any inequality or irregularity in the setting of their guide rails 11 upon the sides of the window frame.

22 designates a vertically depending stop pin or member preferably arranged in a 85 moving manner in each head or block 16 and yieldingly held in a downwardly projected position by gravity preferably aided by a spring 23 as shown in Fig. 4.

24 designates a horizontally extending 90 holding pin or member moving in each head or block 16, and yieldingly held in a projected condition by a spring 25 as shown in Fig. 6.

26 designates a pawl or dog individual to 95 and pivotally mounted on an awning extending arm 17 adjacent to its point of pivotal attachment to a sliding head 16, and having a curved free end or finger 27 adapted for holding abutment against the depending 100 stop pin 22 aforesaid. In the present improvement the pawl or dog 26 is formed with an intermediate shoulder or offset 28 adapted in the operation of the mechanism to drop past the horizontally extending stop 105 pin 24 and release the aforesaid end or finger 27 of the dog or pawl 26 from its holding engagement with the depending stop pin 22 aforesaid.

29 designates an inclined or cam formation on the side of the dog or pawl 26 adjacent to the free end of the pin or stud 24 and adapted in an upward movement of the pawl or dog 26 and associated awning extending arm 17, to push the pin or stud 24 115 out of the way to permit of an unimpeded upward pivotal movement of the awning extending arms 17 and the dog or pawl 26 carried thereon.

The operation of the present mechanism 120 is as follows:—

As the operator draws upon the cord 4 to effect a revolution of the roller 2 and an unwinding of the awning sheet 3, the sliding heads 16 and accessories descend by gravity 125 until said heads 16 rest upon the lower bracket members 13 by which further downward movement of said heads is prevented.

Further unwinding of the awning sheet 3 admits of an outward and downward swing of the awning extending arms 17 and in such movement of said arms, the upper curved surface of each pawl 26 rides under the stop pin 22 of a sliding head 16 until the free end of the dog is past said stop pin 22, when said pin descends behind the point of said dog 26 to lock the awning mechanism in the spread or extended condition shown in Fig. 3, and in such condition of parts, the horizontal stop pin 24 is beneath the dog 26 to maintain the parts in the described locked condition.

When it is desired to release the above described locked condition of the parts, the operator effects a further rotation of the roller 2 and unwinding of the awning sheet 3, which permits of a further downward swing of the awning extending arms 17 to cause the shoulder 28 of each pawl or dog 26 to move past its horizontal bearing pin 24 and permit the pawl or dog 26 to drop by gravity from its previous holding engagement with its vertical stop pin 22. The operator then releases the pull on the cord 4 to permit the spring roller 2 to exert its normal tendency to wind up the awning sheet 3 into a wound condition thereon. In such upward or folding movement of the awning parts, the inclined or cam surface 29 on the side of the pawl or dog 26 is adapted to push the horizontal holding pin 24 to one side so as not to interfere with the said upward movement of parts.

In case of a violent wind storm or other like stress upon the awning sheet 3, the tendency will be to force the lower portion of said awning sheet downward against the tension of the spring roller 2, and when such storm or like stress is sufficiently strong to effect such downward movement of the awning sheet and associated parts, an automatic release of the locking mechanism will take place, in a like manner as the manually actuated release above described.

Having thus fully described my said invention what I claim as new and desire to secure by Letters Patent, is:—

1. In an awning of the type described, the combination of an awning extending arm, a pair of upright side guide rails having guiding engagement with said arm, upper and lower fixed bracket members formed with socket recesses for the ends of said rails, and resilient abutments arranged in the socket recesses of the upper bracket members, substantially as set forth.

2. In an awning of the type described, the combination of an awning extending arm, a pair of upright side guide rails having guiding engagement with said arm, upper and lower fixed bracket members formed with socket recesses for the ends of said

rails, and spring actuated abutment plates 65 arranged in the socket recesses of the upper bracket member, substantially as set forth.

3. In an awning of the type described, the combination of an awning sheet having a transverse stretcher rail at its lower end, a head journaled on an end of said rail, a fixed upright guide rail, a sliding head on said guide rail, and an awning extending arm pivotally connected to said sliding head and to the end head of the stretcher rail by pivot connections, the axes of said pivot connections having a disposition in right-angle relation to each other, substantially as set forth.

4. In an awning of the type described, the combination of an awning sheet having a transverse stretcher rail at its lower end, a head journaled on an end of said rail, a fixed upright guide rail, an awning extending arm connected at one end to said head by a pivot connection the axis of which is transverse to the plane of the mechanism, a fixed upright guide rail and a sliding head on said guide rail having pivotal connection with an end of the awning extending arm, the pivot axis of said connection being longitudinal with the plane of the mechanism, substantially as set forth.

5. In an awning of the type described, the combination of an awning extending arm, a guide rail, a sliding head on said rail having pivotal connection with the arm aforesaid and provided with a vertically disposed stop member and a horizontally disposed holding member, and a pawl pivoted on said arm and having a point portion adapted for holding engagement with the aforesaid vertically arranged stop member and with an intermediate offset portion adapted for operative engagement with the aforesaid horizontally arranged holding member, substantially as set forth.

6. In an awning of the type described, the combination of an awning extending arm, a guide rail, a sliding head on said rail having pivotal connection with arm aforesaid and provided with a vertically movable stop member and a horizontally movable holding member, and a pawl pivoted to said arm and having a point portion adapted for holding engagement with the aforesaid vertically movable stop member and with an intermediate offset portion adapted for operative engagement with the aforesaid horizontally movable holding member, substantially as set forth.

7. In an awning of the type described, the combination of an awning extending arm, a guide rail, a sliding head on said rail having pivotal connection with arm aforesaid and provided with a vertically movable stop member and a horizontally movable hold-

ing member, and a pawl pivoted to said arm and having a point portion adapted for holding engagement with the aforesaid vertically movable stop member, with an intermediate offset portion adapted for operative engagement with the aforesaid horizontally movable holding member and with

a cam surface in a side face for operative engagement with said horizontally movable holding member, substantially as set forth.

Signed at Chicago, Illinois, this 29th day of April, 1919.

HARVEY C. BAKER.
